(57) **CLAIM**

The ornamental design for a dispensing lid, as shown and described.

DESCRIPTION

FIG. 1 is a perspective view of a dispensing lid.

FIG. 2 is a front view thereof.

FIG. 3 is a right view thereof, the left view being a mirror image thereof.

FIG. 4 is a rear view thereof.

FIG. 5 is a top view thereof; and,

FIG. 6 is a bottom view of the dispensing lid shown removed from a bottle for clarity of disclosure.

In FIGS. 1, 2, 3, and 4, the dash-dot lines show portions of a bottle that form no part of the claim.

In FIG. 4, and also in FIGS. 3 and 5, the evenly spaced broken lines show portions of elements of the dispensing lid that form no part of the claim.

In FIG. 6, the evenly spaced broken lines show surfaces on the bottom of the dispensing lid that form no part of the claim.

1 Claim, 6 Drawing Sheets
